UNITED STATES PATENT OFFICE.

GEORGE F. EGAN, OF JERSEY CITY, NEW JERSEY.

DISPLAY DEVICE.

Original application filed August 3, 1925, Serial No. 47,866. Divided and this application filed April 8, 1926. Serial No. 100,618.

The present invention relates to improvements in display devices and constitutes a division of my copending similarly entitled application, filed August 3, 1925, Serial No. 5 47,866.

An object of the invention described and claimed herein is to provide an extremely light and inexpensive, yet strong, device for holding a card, tag and the like in display 10 windows or upon shelves for indicating the cost of goods or some other message in connection with goods.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a perspective view of a display device constructed according to the present invention;

Figure 2 is a similar view showing a modification; and

Figure 3 is a cross section taken on the line 3—3 in Figure 2.

Referring more particularly to Figure 1, the device is shown as made of a single piece 30 of sheet metal bent intermediately of its ends as indicated at 21, and shown as providing two wing portions 22 and 23 at an angle, whereby the device may be set up upon either edge. A relatively wide area 35 of support is provided by this divergent wing structure, which prevents the device from tilting or falling over even when supporting a rather large card.

The upper edges of the wing portions are 40 shown as provided with slots 24 and 25 at substantially the same distance from the angle or corner, whereby to simultaneously receive the lower edge portion of a card. These slots are preferably made at an angle 45 extending downwardly toward the corner portion in order to hold the card at a slight inclination. This inclination of the slots is also useful in avoiding undue weakening of the material, as other slots 26 and 27 are 50 shown made in the lower edge of the wing portions. The inner edges of these slots are spaced apart by the inclination given.

The slots 26 and 27 may be substantially straight or vertical in order to hold the card in an upright position when placed therein. 55 Thus the device admits of variety in the manner of the display of a card.

In Figures 2 and 3 there is provided a device similar to that shown in Figure 1, in which the angle portion 21, wings 22 and 23 are similar, and provided with similar slots, except that the inclination of these slots may vary. The device is shown as having a further substantially horizontal slot 31 extending about the corner portion 21 65 and preferably being in an angle to the vertical when the device is set up upon the edge parts 32 with the corner portion 21 uppermost. In such position the slot 31 is adapted to receive and support a card. In 70 this instance also the slots 26 and 27 may be arranged on an inclination, which is preferably parallel to the slots 24 and 25, in order that the inner face of the slots may be offset as much as possible to avoid reducing 75 the strength of the sheet metal wings and to remove the inner ends of the slots 26 and 27 as far as practicable from the end portions of the slot 31.

It is obvious that various changes and modifications may be made in the details of construction and design of the above specifically described embodiment of this invention without departing from the spirit thereof.

What is claimed is:—

1. A display device comprising a sheet body bent transversely to provide a pair of wings extending at acute angles to one another and adapted to be reversably stood on either end with its angled connecting portion extending substantially vertically, said pair of wings having pairs of mating slots therein, one pair of slots opening through one end of the device and the other pair of slots opening through the other end of the device, said slots being inclined to the vertical in the set-up position of the device with the open mouths of the slots in approximate central parts of the respective wing edges and with the inner parts of the slots in each wing remote from one another.

2. A display device comprising a thin, flat flexible sheet body longer than wide and

bent permanently on its intermediate transverse axis to an acute angle to provide a pair of similar flat wings adapted to be stood triangularly upon either end, said wings having pairs of slots therein to receive cards, one pair of slots opening on one end of the device and the other pair on the opposite end, the mouths of the slots at both ends

being at approximately the central parts of the ends of the wings, the slots at opposite ends of the device extending in relatively opposite diagonal directions from the slots' mouths inwardly into the wings. ¹⁰

In testimony whereof I affix my signature.

GEORGE F. EGAN.
